[57] **CLAIM**

The ornamental design for a film dispenser, substantially as shown.

DESCRIPTION

FIG. 1 is a perspective view of a film dispenser embodying the ornamental features of the new design, showing the dispenser in its closed condition;

FIG. 2 is a similar view showing the dispenser in its open condition;

FIG. 3 is an end elevational view thereof;

FIG. 4 is a rear elevational view thereof;

FIG. 5 is a front elevational view thereof;

FIG. 6 is a top view thereof; and

FIG. 7 is a bottom view thereof.

FIG. 1

FIG. 2

FIG. 3

FIG. 4

FIG. 5

FIG. 6

FIG. 7
